DESIGN.

L. BINNS.

CORD.

No. 18,244.

Patented Apr. 10, 18

1888

UNITED STATES PATENT OFFICE.

LEEDHAM BINNS, OF PHILADELPHIA, PENNSYLVANIA, ASSIGNOR TO
EDWARD H. GODSHULK, OF SAME PLACE.

DESIGN FOR A CORD.

SPECIFICATION forming part of Design No. 18,244, dated April 10, 1888.

Application filed March 14, 1888. Serial No. 267,187. Term of patent 3½ years.

To all whom it may concern:

Be it known that I, LEEDHAM BINNS, a subject of the Queen of Great Britain, residing in the city and county of Philadelphia, State of Pennsylvania, have invented and produced a new and original Design for a Cord, of which the following is a specification, reference being had to the accompanying photograph, forming part thereof.

10 The leading feature of my design for a cord is a row of segments projecting in opposite directions toward each other, forming a zigzag.

In the accompanying photograph, which

represents diametrically opposite sides of the cord embodying my invention, the letter *a* designates segments which are alternately disposed in opposite directions toward each other throughout the length of the cord, thus forming a zigzag of segments.

I claim—

20 A design for a cord having a zigzag of segments, as shown and described.

LEEDHAM BINNS.
